UNITED STATES PATENT OFFICE.

CHARLES C. COGGESHALL, OF EMPORIA, KANSAS.

SKID FOR RAILWAY-CARS.

SPECIFICATION forming part of Letters Patent No. 533,209, dated January 29, 1895.

Application filed May 24, 1894. Serial No. 512,253. (No model.)

To all whom it may concern:

Be it known that I, CHARLES C. COGGESHALL, of Emporia, in the county of Lyon and State of Kansas, have invented a new and useful Improvement in Skids for Railway-Cars, of which the following is a specification.

My invention relates to an improvement in skids for railway cars, in which provision is made for sliding the skid into and out of operative position in front of the car door, the skid itself being constructed to fold into a compact form and rest, when out of use, along the side of the car within convenient reach of a person in the neighborhood of the car door.

15 A practical embodiment of my invention is represented in the accompanying drawings, in which—

Figure 1 represents a portion of a car in side elevation, showing the skid in operative position in front of the car door. Fig. 2 shows the skid in the position which it assumes when it has been swung to one side of the car door in the operation of folding it. Fig. 3 is a top plan view, showing the position of the skid 25 when folded and out of use, and Fig. 4 is an enlarged view in detail of one end of one of the skid rails, showing the elongated slot through which the supporting rod passes.

The side of the car is denoted by A and the 30 door by a. Along the door sill, a supporting rod B is fixed, spaced a short distance from the side of the car and, extending—preferably—a short distance beyond the opposite sides of the door. The rod B may be conveniently provided at one end with a bracket b, formed integral therewith, and provided with holes for the reception of bolts or other suitable fastening devices for securing the end firmly to the car and at its opposite end the 35 said rod may be provided with a screwthreaded portion b' for the reception of the nut b². The end b' is intended to pass through a perforation in a bracket C, fixed to the side of the car, and the rod B is intended to be secured 40 and stiffened by turning the nut b² on the threaded portion b' against the face of the bracket C.

The skid consists of a pair of side rails D, D', preferably connected by one or more tie-bars E, E'. In the present instance I have

shown two such tie-bars. The ends of the rails D, D' of the skid, toward the car, are provided with slots d, (see Fig. 4) through which the supporting rod B extends to secure the skid to the car. The slots d are sufficiently 55 elongated to permit the bars to swing, when in a horizontal position, toward and away from the side of the car without cramping.

To afford the rails an extended bearing and give them more rigidity, when in use, I turn 60 their ends, as shown at d' (see Fig. 2) at right angles to the body portions, so that when the supporting rod B rests in contact with the ends of the slots d nearest the ends of the rails, the laterally turned portions d' will bear 65 against the supporting rod B, as shown in Fig. 1.

The tie-bars E, E' may be joined to the rails D, D' in any well known or approved manner so as to permit the rails D, D' to fold toward and away from each other. In the present instance I have shown the tie-bars E and E' connected by pivot rivets e, with lugs d² on the rails D, D'.

When the skid is out of use, it may be slid 75 laterally along the supporting bar B until one of its rails, D for example, reaches the end of the support B, and it then may be folded together into the position shown in Fig. 3 and its free end permitted to rest in a hook 80 bracket F, fixed to the car. In this position, the skid is well out of the way and is at the same time so located that it may be quickly and readily thrown out of its support F and swung around in front of the car door, as 85 shown in Fig. 1, for the purpose of sliding trunks or freight, either onto the ground or onto the platform at the side of the track, or onto another car located at the side of the car to which the skid is attached. 90

The skid, when constructed as above described, may be made of sufficient length to be practical for all ordinary transfers of baggage or freight and at the same time when out of use occupies a very small space at the 95 side of the car.

It is obvious that slight changes might be resorted to in the form and arrangement of the several parts without departing from the spirit and scope of my invention. Hence I 100

do not wish to limit myself strictly to the structure herein set forth, but

What I claim is—

1. The combination with a rod constructed to be secured horizontally along the sill of a door, of a skid comprising a pair of side rails slotted to receive the bar, and connected by one or more tie bars pivotally secured to the side rails the said rails being adapted to swing on the bar toward and away from each other into and out of folded adjustment and means for supporting the skid when out of use, substantially as set forth.

2. The combination with a supporting bar, of a skid comprising a pair of side rails slotted to receive the bar and having their ends turned at an angle to their body portions to engage the supporting bar when the rails are in operative position on the supporting bar, and one or more tie bars pivotally connected with the side rails substantially as set forth.

CHAS. C. COGGESHALL.
